UNITED STATES PATENT OFFICE.

FRANK E. BUDDINGTON, OF STILLWATER, MINNESOTA.

DRESS-MAKER'S MEASURE FOR CUTTING DRESSES AND OTHER ARTICLES OF CLOTHING.

SPECIFICATION forming part of Letters Patent No. 272,204, dated February 13, 1883.

Application filed July 15, 1882. (Model.)

To all whom it may concern:

Be it known that I, FRANK EUGENE BUDDINGTON, of Stillwater, in the county of Washington and State of Minnesota, have invented 5 a new and useful Improvement in Dress-Makers' Measures for Cutting Dresses and other Articles of Clothing, of which the following is a full, clear, and exact description.

Reference is to be had to the accompanying 10 drawings, forming part of this specification, in which similar letters of reference indicate corresponding parts in all the figures.

Figure 1, Sheet 1, is a plan view of the back-measure. Fig. 2, Sheet 1, is a sectional elevation 15 of a part of the same, taken through the line $x-x$, Fig. 1. Fig. 3, Sheet 1, is a plan view of the end of one of the sliding bars enlarged. Fig. 4, Sheet 1, is a plan view of the front-measure. Fig. 5, Sheet 1, is a sectional elevation of a 20 part of the same, taken through the line $y-y$, Fig. 4. Fig. 6, Sheet 2, is a plan view of the dart-rule.

The object of this invention is to facilitate 25 the cutting of dresses and other articles of clothing.

The invention consists in the measure for cutting dresses and other articles of clothing, constructed with cutters formed of bars, sheaths, and slides for drawing the outlines of the back 30 and front patterns, and a dart-rule for drawing straight and curved lines, as will be hereinafter fully described.

My improvement consists of three main parts, 35 called by me the "back-measure," the "front-measure," and the "dart-rule," which are marked, respectively, A B C in the drawings. In the back-measure A, D is the back-bar to receive the back-measures, and to its upper end 40 is soldered or otherwise secured a small plate, E, to which is also soldered or otherwise secured the upper end of the tubular sheath F. The sheath F stands at an acute angle with the back-bar D, as shown in Fig. 1, and within it slides the bar G, which receives the shoulder-measures.

At the middle and lower parts of the back-bar D are placed the slides H I, to which are soldered or otherwise secured the ends of the sheaths J K. In the sheath J is placed a bar, L, to receive the bust-measures, and in the sheath K is placed a bar, M, to receive the 45 waist-measures.

To the outer ends of the bars L M are attached rivets N, the heads of which slide between the edges of the bar O. The bar O 55 serves as a guide in marking out the back-pattern, and to its upper end is hinged by a rivet the lower end of the arm-scye bar P, the upper end of which is hinged by a rivet to the end of the shoulder-bar G. The edges of the bars G 60 L M are turned over to receive and protect the measure-scales, which are printed upon paper and cemented to the said bars. The edges of the bar D are turned over to receive and protect the measure-scale, and to serve as ways for 65 the slides H I; and the edges of the bar O are turned over to serve as a way for the rivets N. The bars D G L M O are also strengthened and stiffened by having their edges turned over, so that they can be made light.

To the ends of the bars G L M are attached 70 small springs Q, which press against the inner surfaces of the sheaths F J K, and thus hold the said bars in place.

In using the back-measure A the measurements are taken from the body of the person to be fitted, and the slides H I and the bars G 75 L M are adjusted to the figures upon the measure-scales representing the said measurements. The cutter A is then laid upon paper or cloth, 80 and the said paper or cloth is then marked around the outer edge of the said measure A, which gives the outline of the back-pattern for the dress.

In the front-measure B, R is the front-bar, to 85 the upper end of which is attached the neck-bar S. In the neck-bar S slides the neck-slide T, to the outer end of which, and projecting downward at an obtuse angle, as shown in Fig. 4, is attached the shoulder-bar U.

At the middle and lower parts of the front-bar R are placed the slides V W. To the slide V is attached the bust-bar X, in which slides the bust-slide Y. To the lower end of the slide V is attached the end of the wire Z, which is 95 intended to locate the top of the darts, and the upper end of which is curved upward and is secured to the outer end of the bust-bar X.

To the slide W is attached the end of the 90 waist-bar a, in which slides the waist-slide b. To the outer end of the waist-slide b is attached the lower part of the under arm bar c, in the upper part of which slides the head of a rivet, d, attached to the end of the bust-slide Y.

The edges of the bars R, S, U, X, and *a* are turned over to strengthen and stiffen them, and to receive and protect the scales of measures. The edges of the slides T, V, W, Y, and *b* are turned over to strengthen and stiffen them, and to cause them to move more freely in the bars R, S, X, and *a*. The turned-over edges of the bars also serve as springs to hold the slides in place when adjusted.

10 In using the front-measure B the measures are taken from the body of the person to be fitted, and the slides are adjusted to the numbers upon the corresponding scales. The measure is then laid upon paper or cloth, and the 15 said paper or cloth is marked around the outer edge of the cutter which forms the front-pattern.

The dart-rule C is designed to be used for drawing straight and curved lines, and is also provided with front, neck, arm-seye, and children's measure-scales, and with a dart-table.

With these devices, by taking the body-measures carefully and adjusting the various parts of the measures accurately, a neat-fitting dress will be produced without any change of 25 seams being necessary.

Having thus fully described my invention, I claim as new and desire to secure by Letters Patent—

1. A measure for cutting dresses and other 30 articles of clothing, constructed substantially as herein shown and described, and consisting of the back-measure A, formed of the bars D

G L M O P, the slides H I, the sheaths F J K and the plate E, the front-measure B, formed of the bars R S U X *a* *c*, the slides V W, the 35 slide-bars T Y *b* and the wire Z, and the dart-rule C, as set forth.

2. In a measure for cutting dresses and other articles of clothing, the combination, with the bar D and the connecting-plate E, of the slides 40 H I, the sheaths F J K, the sliding bars G L M, the adjustable bar O, and the hinged bar P, substantially as herein shown and described, whereby the measure can be adjusted to give the outline of a dress-back pattern, as set forth. 45

3. In a measure for cutting dresses and other articles of clothing, the combination, with the bars R S, of the slides V W, the bars U X *a*, the slide-bars T Y *b*, the adjustable bar *c*, and the wire Z, substantially as herein shown and 50 described, whereby the measure can be adjusted to give the outline of a dress-front pattern, as set forth.

4. In a measure for cutting dresses and other articles of clothing, the dart-rule C, made with 55 straight and curved edges, and provided with front, neck, arm-seye, and children's measure-scales, and with a dart-table, substantially as herein shown and described.

FRANK E. BUDDINGTON.
